UNITED STATES PATENT OFFICE.

MURDICK CAMERON, OF DULUTH, MINNESOTA, ASSIGNOR OF ONE-HALF TO
GEORGE L. WOOLEN, OF ST. LOUIS COUNTY, MINNESOTA.

ROTARY ENGINE.

SPECIFICATION forming part of Letters Patent No. 729,042, dated May 26, 1903.

Application filed September 15, 1902. Serial No. 123,368. (No model.)

To all whom it may concern:

Be it known that I, MURDICK CAMERON, a citizen of the United States, residing at Duluth, Minnesota, have invented certain new and useful Improvements in Rotary Engines; and I do hereby declare the following to be a full, clear, and exact description of the invention, such as will enable others skilled in the art to make and use the same.

10 My invention relates to rotary engines.

It consists of certain constructions, combinations, and arrangements of parts, as will be hereinafter more particularly set forth and described.

15 In the accompanying drawings, Figure 1 is a central vertical cross-sectional view of my said invention. Fig. 2 is an enlarged detail of the piston and portion of the piston-wheel, as shown in Fig. 1. Fig. 3 is an enlarged 20 tail end view of said piston and of a portion of the side of the piston-wheel. Fig. 4 is a perspective detail of the head of one of the standards supporting the power-shaft. Fig. 5 is a reduced central vertical cross-section 25 of the casing of said piston-wheel and of a part of the casing of the feed and exhaust or reversing valve-cylinders. Fig. 6 is a diagram showing the course of the piston guide-wheel around the piston-wheel casing or 30 housing. Fig. 7 is an enlarged detail, in vertical cross-section, of a portion of said valve-casing and of the inclosed steam-feed cylinder and of a portion of the inclosed exhaust and reversing cylinder. Fig. 8 is a reduced 35 side elevation of the interior face of one of the halves of the piston-wheel casing, showing in vertical longitudinal section a portion of the supporting-base and in vertical cross-section a portion of the said valve-casing and 40 valve-cylinders. Fig. 9 is a similar view of the other half of said piston-wheel casing and base and valve casing and cylinder. Fig. 10 is a detail end elevation of said valve-casing and of the projecting valve-stem of the steam-feed valve and of the eccentric valve-operating mechanism. Fig. 11 is an enlarged detail of one end of the exhaust and reversing cylinder.

45 In the drawings, 1 is a base, having a shaft-supporting standard 2 formed thereon or secured thereto and having another shaft-supporting standard 3 removably secured there-

to by a key 4, or any other or additional suitable means, each of which standards is formed with a head 5, having a projecting lip 6, preferably grooved, as at 7, to receive a suitable key, which head is adapted to form one half of a journal-box, upon which is removably secured, by any suitable means, a corresponding half or cap 8, preferably formed with a projecting lip 9, grooved, as at 10, to receive a key, hereinafter described. Secured to said base in any suitable manner, as by bolts 11, I erect one half of a piston-wheel casing 12, to which I bolt the other half 13 of said casing, which casings are respectively recessed in their opposing faces, as at 14, to receive a piston-wheel, hereinafter described. The part 12 is further recessed, as at 18, to receive the flange of a sleeve, hereinafter described, and is apertured, as at 19, to receive the power-shaft and an encircling sleeve. The part 13 is similarly recessed, as at 15, to receive the hub of the piston-wheel and apertured, as at 16, to receive the reduced portion of said hub and 55 said shaft and is preferably also recessed in its exterior face, as at 17, to receive the end of a collar, hereinafter described. Each half of said casing may also be recessed, as at 20, to lighten the metal and to lessen friction between the faces of said casing and the contained piston-wheel. The inner faces of each half of said casing are also further recessed, so that when said halves are brought together 60 said last-described recess will form an annular groove 21, lying wholly in part 12 throughout approximately half its course and dipping gradually from the points *x* and *z*, respectively, into part 13, from both directions, for the remainder of its course, until it lies 65 wholly in said part 13 at the point *y*, forming a transverse shoulder 14^a on the part 12, and an indent 14^b in the part 13. Said part 12 is further formed with an annular groove 22 in its inner face, interrupted at one point by an 70 abutment 12^a, hereinafter described. Said wheel 23 may be keyed directly to a power-shaft 28, but is preferably recessed in one face, as at 26, to receive a core 27, to which 75 it is slidably secured by a suitable loose key, 80 said core being in turn secured to said shaft by a tight key, the object of which is to lessen the lost motion which would occur if the wheel 23 were slidably keyed directly to the 85 shaft 28. The base 1 is provided with a 90

95

100

shaft by a loose key. A sliding sleeve 29 is also keyed to said shaft by a loose key, which sleeve is projected through the aperture 19 of said part 12 prior to the positioning of, said 5 wheel in said casing and is formed with a flange at its inner end, adapted, in operation, to bear against the face of said wheel 23, and said sleeve is externally threaded at its outer end to engage the internally-threaded flange of an adjusting-collar 30, loosely mounted upon said shaft and adapted to abut against a fixed eccentric collar 31, secured to said shaft by a set-screw, as shown, or by any other suitable means, by which construction 10 the revolution of said collar 30 in one direction will thrust said sleeve 29 inwardly against the wheel 23, and the opposite revolution of said last-named collar will draw it upon said sleeve away from said collar 31, permitting 15 the wheel 23 to press said sleeve outwardly a limited distance. To adjustably block the shaft itself against longitudinal movement in one direction, I provide the loose collar 32, mounted on said shaft and 20 slidably keyed to the lips 7, or 10, or both of them, by loose keys projecting into the grooves of said lips, respectively, which collar is formed with a reduced hub, externally threaded to engage an internally-threaded loose 25 collar 33, mounted on said hub and adapted to bear against the inner face of said journal-box, whereby the revolution of said collar 33 in one direction will force said sliding collar 32 inwardly against the face of the fixed collar 31. A collar 34, similar to said 30 collar 33, is mounted upon said shaft on the opposite side of said wheel-casing and is adapted to engage the externally-threaded end of the extension 25 of said wheel-hub 35 and to bear against a stiff coiled spring 35, mounted on said shaft, which spring, in turn, is adapted to bear against a fixed collar 36, secured to said shaft, by which means said wheel 23 may adjustably be kept under 40 spring tension close against the inner face of part 12, with due allowance for expansion in the direction of part 13 and with but trifling friction against the inner face of said part 12. The parts 37 and 38 are oppositely-directed, 45 50 similar parts to said collars 32 and 33 and prevent the movement of the shaft in the opposite direction. To secure further rigidity of said standards 2 and 3 and to correct any warping of the same, I preferably provide the 55 right and left threaded spacing-bolts 39, adapted to engage recessed studs 40, respectively secured to said standards and to the outer side faces of said wheel-casings and internally threaded to respectively correspond 60 to and receive the threaded ends of said spacing-bolts. At opposite points near the periphery of said wheel 23 I arrange transversely-sliding pistons 41, each inserted in a transverse aperture or recess formed in said 65 wheel, which pistons are adapted, in retracted position, to be housed entirely within said recesses 41 and, in operative position, to

project therefrom into the groove 22 of said casing and when fully projected to fill said groove. A slot 43 is formed in the periphery 70 of said wheel, connecting with said recess 42, through which slot a pin 44 is projected into said piston 41 for the purpose of sliding said piston back and forth, which pin is provided at its outer end with a guide-wheel 45, adapted to travel in said groove 21 of the wheel-casing and to thrust forth or retract said piston, accordingly as the course of said groove 21 shall govern the transverse movement of said guide-wheel. A groove is also preferably 80 cut in said wheel 23 from the interior of said recess 42, into which groove is sprung a split ring-spring 46 and four overlapping sections of packing lying within the said ring-spring and adapted to bear against the piston 41 at 85 its sides and upper and lower edges. A groove is also preferably cut vertically in the forward edge of said piston and continued in the top and bottom edges of the forward part of said piston, the rearward ends of said groove being joined by a recess in said piston, which groove and recess will form an elliptical channel, deeper at each end of the ellipse than at the top and bottom, into the rearward end of which is preferably sprung a flat spring 48 95 and into which elliptical channel, forward of said spring 48, is sprung a packing-ring 50, inclosing the portion 49 of said piston, the said ring 50 being divided, as at 51, the divided ends preferably overlapping, but the 100 said method and means for packing said piston may be altered, or modified, as may seem desirable, or may be wholly omitted. A faucet 52 is preferably provided for drawing off condensed steam from said groove 22. 53 and 105 53^a are combined steam feed and exhaust ports, respectively communicating with the groove 22 on opposite sides of the abutment 12^a, said port 52 normally also communicating with the branch 57^b of the valve 57, and 110 the port 53^a at the same time communicating with an exhaust-port 59 through the wall of cylinder 56, Fig. 9, by which steam is exhausted into the chamber of said cylinder and thence out through a 115 pipe 69^a to the atmosphere. When it is desired to reverse the engine, the cylinder 56 is rotated, so that the port 59 and the mouth of the branch 57^b are closed against the casing 55 and the casing 12, respectively, and at the 120 same time a peripheral groove 54^a, formed in said cylinder 56, is brought into communication with branch ports 54 and 54^b of said ports 53 and 53^a, respectively, whereby part of the steam on one side of the abutment 12^a passes 125 through said ports, branch ports, and groove to the opposite side of said abutment. The rotation of said cylinder 56 is continued until said groove passes beyond said branch ports and the branch 57^b comes into registration 130 with said port 53^a and an exhaust-port 58, similar to said port 59, comes into registration with said port 53, at which time the branch 57^a, of said valve 57, will have been

closed against the wall of casing 55 and the branch 57^c will have come into registration with the port 60, leading into said steam-cylinder 61. A steam-supply pipe 62 constantly 5 communicates with a port leading through said casing 55, which latter port communicates constantly with an elliptical port leading into said steam-cylinder. In said pipe 62 any suitable governing-valve (not shown) 10 may be located and controlled by any suitable governor connected in any suitable manner by an eccentric mechanism with said power-shaft, such devices being well known in the art and not thought necessary to be 15 particularly described herein. Spiders 63 are secured in the ends of said steam-cylinder, into which is keyed a central shaft 64. A similar spider is secured in one end of the reversing-cylinder, in which a shaft 66 is keyed, 20 and a reversing-lever 66^a is secured to the outer end of said shaft 66, by means of which, said cylinder is rotated to reverse the engine. Covers 67 are bolted to said casing 55, to cover the ends of said steam and reversing cylinders and may also be bolted to said parts 12 25 and 13. A crank 69 is secured to one end of the shaft 64 and pivoted at its outer end in the upper end of a connecting-rod 70, which is pivoted at its lower end to one end of an 30 adjustable rocker 71, which is pivoted, through a central slot, to a stud 72, projecting from said part 12, which rocker is pivoted at its opposite end to the rod of an eccentric-strap encircling the eccentric collar 31, by which 35 means the steam-cylinder is rocked to partly cut off steam from said valve 57.

While I have described the essential part of said engine comprising my invention, it is obvious that suitable ball-bearings, oil-cups, 40 governor, and other well-known details may be added and that the construction of said engine may be modified in minor particulars within the scope of said invention.

The operation of said invention is as follows: Steam is preferably continuously admitted under full head to said steam-cylinder 61 and continuously to the port 60 thereof, flowing through said port when any of the branches of said valve 57 are in registration 45 therewith. The branch 57^a being in registration with port 60 when said engine is working ahead, steam flows through said branch 57^a into branch 57^b and through said port 53 into the groove 22 forward of said abutment 55 12^a, escaping, in part, past the end of the piston, which is between the abutment and the point *x*, and flowing with direct and expanding pressure against the full face of the farther piston, which is between the points 60 *x* and *z* in the lower plane of said casing 12. When said farther piston reaches the point *z*, it begins to retract, permitting the steam to pass it and escape through the ports 53^a and 59 into the exhaust or reversing cylinder 65 56, and thence out to the atmosphere through the pipe 69^a. At the moment said farther piston begins to retract at the point *z* the other pis-

ton will reach the limit of its projection into said groove 22 at the point *x* and will shut off the steam from said further piston, thence 70 receiving the full head of steam from the point *x* to a point intermediate of the point *x* and the point *z* and opposite said abutment. When said last-named piston passes said intermediate point, said farther piston will pass 75 the abutment and begin to be projected into said groove 22 and to gradually cut off the steam from the piston between said intermediate point and said point *z*. To reverse said engine, the reversing-cylinder 56 is partly rotated by means of the lever 66^a, so as, first, 80 to close the inlet and exhaust ports 53 and 53^a, respectively, and, continuing, bring said groove 54^a over both said branch ports 54 and 54^b, through which the live steam from the 85 positive side of the abutment 12^a can then enter at the reverse side of said abutment and fill the groove between abutment and said farther piston, whereby the impulse from the steam subsequently admitted to said groove, 90 on the reverse side of said abutment, from said cylinder 61 will be the sooner felt on the face of the retreating said farther piston. The rotation of said cylinder 56 being continued, 95 said branch 57^b will be brought into registration with said port 53^a, and said branch 57^c will be brought into registration with said port 60, and said branch 57^a will be closed 100 against the casing 55, and said exhaust-port 58 will be brought into registration with said port 53, and the groove 54^a will be closed 105 against said casing 12 and 55.

Having now described my invention, what I claim, and desire to secure by Letters Patent, is—

1. In a rotary engine, the combination with a suitable base of two vertically-arranged housings adapted in coöperation to inclose a piston-wheel and respectively so grooved in the interior faces of their flanged portions that when said housings are brought together in operative position said grooves will coöperate to form one annular groove, the bottom of which shall, for approximately half its course, lie wholly within one of said housings, 110 and for the remainder of its course deviate to the opposite said housing until it comes wholly within said opposite housing, the housing containing the major part of said groove being also formed with an annular groove in 115 its interior side face, obstructed by an abutment filling said groove at a point opposite to where the first said groove comes wholly within said opposite housing, and having steam inlet and exhaust ports connecting 120 with the second said groove on either side of said abutment respectively, a power-shaft projected transversely through said housings, a piston-wheel concentric to said shaft and keyed thereto within said housings and 125 adapted to closely approach the side face of the housing containing the second said groove and to cover said groove, and to broadly clear the inner side face of the opposite said hous-

ing, pistons, carried in recesses formed in said wheel near the periphery thereof, and adapted to be projected into said groove and to be retracted into said recesses respectively, 5 pins secured to said pistons and projecting through peripheral, transversely-prolonged slots formed in said wheel, guide-wheels carried by said pins, respectively and adapted to travel in the first-said groove to govern the 10 position of said pistons, means for supplying steam or other motive gas or liquid to either one of said ports and means for conveying the exhaust from the other of said ports according as the engine is running ahead, or 15 reversed, adjustable means for effecting a steam-tight approach of the opposing face of said wheel to the inner side face of said housing containing the second said groove, substantially as described.

20 2. In a rotary engine the combination with a suitable base of two vertically-arranged housings adapted in coöperation to inclose a piston-wheel and respectively so grooved in the interior faces of their flanged portions that 25 when said housings are brought together in operative position said grooves will coöperate to form one annular groove, the bottom of which shall, for approximately half its course, lie wholly within one of said housings, 30 and for the remainder of its course deviate to the opposite said housing until it comes wholly within said opposite housing, the housing containing the major part of said groove being also formed with an annular groove in 35 its interior side face, obstructed by an abutment filling said groove at a point opposite to where the first said groove comes wholly within said opposite housing, and having steam inlet and exhaust ports connecting with the 40 second said groove on either side of said abutment respectively, a power-shaft projected transversely through said housings, a piston-wheel concentric to said shaft and slidably keyed thereto within said housings and adapted to closely approach the side face of the 45 housing containing the second said groove and to cover said groove, and to broadly clear the inner said face of the opposite said housing, pistons, carried in recesses formed in said wheel near the periphery thereof, and adapted to be projected into said groove and to be retracted into said recesses respectively, 50 pins secured to said pistons and projecting through peripheral, transversely-prolonged 55 slots formed in said wheel, guide-wheels carried by said pins, respectively, and adapted to travel in the first said groove to govern the position of said pistons, means for supplying steam or other motive 60 gas or liquid to either one of said ports and means for conveying the exhaust from the other of said ports according as the engine is running ahead, or reversed, adjustable means 65 for limiting the approach of the said wheel to the inner side face of the housing containing the second said groove, substantially as described.

3. In a rotary engine, the combination with a suitable base of two vertically-arranged housings adapted in coöperation to inclose a 70 piston-wheel and respectively so grooved in the interior faces of their flanged portions that when said housings are brought together in operative position said grooves will coöperate to form one annular groove, the bottom 75 of which shall, for approximately half its course, lie wholly within one of said housings, and for the remainder of its course deviate to the opposite said housing until it comes wholly within said opposite housing, the 80 housing containing the major part of said groove being also formed with an annular groove in its interior side face, obstructed by an abutment filling said groove at a point opposite to where the first said groove comes 85 wholly within said opposite housing, and having steam inlet and exhaust ports connecting with the second said groove on either side of said abutment respectively, a power-shaft projected transversely through said housings, 90 a piston-wheel concentric to said shaft and slidably keyed thereto within said housings and adapted to closely approach the side face of the housing containing the second said groove and to cover said groove, and to broadly 95 clear the inner side face of the opposite said housing, pistons, carried in recesses formed in said wheel near the periphery thereof, and adapted to be projected into said groove and to be retracted into said recesses respectively, 100 pins secured to said pistons and projecting through peripheral slots formed in said wheel, guide-wheels carried by said pins, respectively, and adapted to travel in the first said 105 groove to govern the position of said pistons, means for supplying steam or other motive gas or liquid to either one of said ports and means for conveying the exhaust from the other of said ports according as the engine is running ahead, or reversed, adjustable means 110 for limiting the approach of the said wheel to the inner side face of the housing containing the second said groove, substantially as described.

4. In a rotary engine, the combination with 115 a suitable base of two vertically-arranged housings adapted in coöperation to inclose a piston-wheel and respectively so grooved in the interior faces of their flanged portions that when said housings are brought together 120 in operative position said grooves will coöperate to form one annular groove, the bottom of which shall, for approximately half its course, lie wholly within one of said housings, and for the remainder of its course deviate to 125 the opposite said housing until it comes wholly within said opposite housing, the housing containing the major part of said groove being also formed with an annular groove in its interior side face, obstructed by an abutment 130 filling said groove at a point opposite to where the first said groove comes wholly within said opposite housing, and having steam inlet and exhaust ports connecting with the second said

groove on either side of said abutment respectively, a power-shaft projected transversely through said housings, a piston-wheel concentric to said shaft and slidably keyed thereto within said housings and adapted to closely approach the side face of the housing containing the second said groove and to cover said groove, and to broadly clear the inner side face of the opposite said housing, piston, carried in recesses formed in said wheel near the periphery thereof, and adapted to be projected into said groove and to be retracted into said recesses respectively, pins secured to said pistons and projecting through peripheral, transversely-prolonged slots formed in said wheel, guide-wheels carried by said pins, respectively, and adapted to travel in the first said groove to govern the position of said pistons, means for supplying steam or other motive gas or liquid to either one of said ports and means for conveying the exhaust from the other of said ports according as the engine is running ahead, or reversed, adjustable means for preventing the longitudinal movement of said shaft, substantially as described.

5. In a rotary engine, the combination with a suitable base of two vertically-arranged housings adapted in coöperation to inclose a piston-wheel, and respectively so grooved in the interior faces of their flanged portions that when said housings are brought together in operative position said grooves will coöperate to form one annular groove, the bottom of which shall for approximately half its course lie wholly within one of said housings and for the remainder of its course deviate gradually to the opposite said housing until it comes wholly within said opposite housing, the housing containing the major part of said groove being formed with an annular groove in its interior side face obstructed by an abutment filling said groove at a point opposite to where the first said groove comes wholly within said opposite housing and having two ports connecting with the second said groove, respectively on opposite sides of said abutment and penetrating the wall of said housing, means for directing a supply of live steam to either one of said ports and means for conveying exhausted steam from the other of said ports, and comprising a hood secured to said housing over said ports, a reversing-cylinder within said hood adapted to be partly rotated and having exhaust-ports formed in the wall thereof of one of which exhaust-ports is adapted, when said engine is running ahead, to register with one of the ports leading to said groove and the other to be closed against the wall of said hood, and said other exhaust-port being adapted, when said cylinder is rotated to reverse said engine, to register with the other of said ports leading to said groove, and the first of said ports in said reversing-cylinder being then adapted to be closed by the wall of said hood, also comprising a three-way valve constructed in said cylinder, one of the

branches of which is adapted when said engine is moving ahead, to communicate with one of the ports leading to said groove and another of the branches of which is adapted to communicate through a port in said hood with the port of a steam-chest contained in another compartment of said hood, and the third branch of which valve is adapted to be closed by the wall of said hood, and said third branch being adapted, when said cylinder is rotated to reverse said engine, to communicate with said ports leading to said steam-chest and said second branch being then adapted to be closed against the wall of said hood and the first said branch being then adapted to communicate with the other port leading to said groove, the housing containing the second said groove having branch ports formed therein connecting respectively at their inner ends with the other said ports formed in said housing and adapted to be normally closed at their outer ends by the wall of said reversing-cylinder and, during the reversing movement of said cylinder, to each communicate with a groove formed in the wall of said cylinder and closed at each end by said hood, said hood being provided with side walls covering the ends of said steam-chest and reversing-cylinder, means for conducting the exhaust from said reversing-cylinder through said hood and away from said cylinder, a supply-pipe for conveying steam or other motive power to said steam-chest, a valve-stem for rocking said steam-chest to partly cover and alternately uncover the port penetrating the division-wall of said hood, an eccentric mechanism connected to said stem and to the power-shaft for operating said valve-stem, and a lever for partly rotating said reversing-cylinder, substantially as described.

6. In a rotary engine, the combination with a suitable base of a piston-wheel housing supported thereby, said housing having an annular groove or irregular course formed in the interior face of its cylindrical wall and an annular groove formed in the interior face of one of its side walls, obstructed at one point by an abutment filling said groove, and having a steam feed and exhaust port connecting with the second said groove respectively on opposite sides of said abutment, a power-shaft projected through said housing, a wheel slidably keyed to said shaft, within said housing, and carrying pistons, adapted to be projected into the second said groove, piston-governing means extending from said pistons into the first said groove, means for supplying steam, or other motive gas or liquid, to one of the ports connecting with the second said groove, means for conducting the exhaust from the other of said ports, adjustable means for governing the position of said wheel on said shaft and comprising a thrust-collar screwed upon a hub formed upon one side of said wheel, a stop-collar rigidly secured to the adjoining end of said shaft, a

spring interposed between said stop-collar and said thrust-collar, a sleeve slidably keyed to said shaft, on the opposite side of said wheel, and having a flange formed upon its 5 inner end, adapted to bear against the adjoining face of said wheel and to register with a concentric recess formed in the adjoining face of said housing and adapted to house said flange, and having its outer end projected 10 through the side wall of said housing, a thrust-collar screwed upon the outer end of said sleeve, a stop-collar rigidly secured to said shaft outward of said thrust-collar, the con-

struction being such that said wheel may be forced from one side under spring tension to 15 a steam-tight approach to the wall of said housing containing the second said groove, and so limited in such approach from the opposite side as to prevent excessive friction, substantially as described. 20

In testimony whereof I hereunto subscribe my signature in presence of two witnesses.

MURDICK CAMERON.
